FIG. 1 is a perspective view of a decorative multi-strand lighting assembly in a fully extended orientation according to my new design.

FIG. 2 is a left side elevation view of a hook portion of the decorative multi-strand lighting assembly in an open orientation. A right side elevation view thereof is a mirror image of the left side elevation view.

FIG. 3 is a left side elevation view of a hook portion of the decorative multi-strand lighting assembly in a closed orientation. A right side elevation view thereof is a mirror image of the left side elevation view.

FIG. 4 is a front elevation view of a hook portion of the decorative multi-strand lighting assembly.

FIG. 5 is a top plan view of a light strand portion of the decorative multi-strand lighting assembly in a fully extended orientation. A rear plan view thereof is a mirror image of the top plan view; and,

FIG. 6 is a partial perspective view of the decorative multi-strand lighting assembly in a loosely hanging orientation. The broken lines shown in each of FIGS. 1, 5, and 6 depict light bulbs, which form no part of the claimed design.
